[57] CLAIM

The ornamental design for a decorative disposable candle-shaped lighter, as shown and described.

DESCRIPTION

FIG. 3 is a left side elevational view of the decorative disposable candle-shaped lighter of FIG. 1;

FIG. 4 is a right side elevational view of the decorative disposable candle-shaped lighter of FIG. 1;

FIG. 5 is a top plan view of the decorative disposable candle-shaped lighter of FIG. 1; and,

FIG. 6 is a bottom plan view of the decorative disposable candle-shaped lighter of FIG. 1.

The broken lines showing of a flame in FIGS. 1, 2, 3, and 4 are for illustrative purposes only and form no part of the claimed design.
